UNITED STATES PATENT OFFICE.

ALBERT H. A. SCHUMACHER, OF COLUMBUS, OHIO.

AUTOMATIC RAILWAY-TRAIN STOP.

Application filed August 14, 1922. Serial No. 581,630.

To all whom it may concern:

Be it known that I, ALBERT H. A. SCHUMACHER, a citizen of the United States, residing at Columbus, in the county of Franklin and State of Ohio, have invented certain new and useful Improvements in Automatic Railway-Train Stops, of which the following is a specification.

The present invention is directed to improvements in automatic railway train stops, and has for its object to provide a device of this kind which is of a portable nature to form a part of the flagman's equipment.

A further object of the invention is to provide a device of this character which can be easily and quickly secured upon one of the track rails, and in a position to engage a trip lever associated with the train braking system to actuate the same to automatically apply the brakes and bring the train to a stand still should the engineer disregard the signal.

It frequently occurs that a train is compelled to stop for unforeseen reasons, and it is necessary that the crew of an oncoming train be notified that the track is not clear, and it has been customary to place a torpedo on the track to notify the approaching train of the danger, and at night time fuses are placed on the track and as is well known these burn for a predetermined time to indicate that the track is obstructed. My invention aims to provide means for supporting a fusee on the device, which when burned out will automatically release the device to permit trains to continue on their way without stopping, but should the engineer disregard the fusee signal the train will be brought to a stand still.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a front view of the device showing it in place on a rail.

Figure 2 is a side view of the device.

Figure 3 is a longitudinal sectional view, and

Figure 4 is a top plan view.

The device comprises a sheet metal clamp 1, which is adapted to be clipped upon a

standard rail 2, said clamp having fixed to one side thereof a horizontal platform 3, said platform having a set screw 4 located adjacent its inner end and adapted to be manipulated to engage the head of a rail should said rail be undersize.

Fixed to the platform 3 are spaced guides 5, and in which are slidably mounted a plate 6, said plate having a perforation 7 formed therein, the purpose of which will appear later. Also carried by the platform 3 are spaced ears 7' and pivotally connected between said ears is the lower end of a trip arm 8, said trip arm having its lower end provided with a right angle flange 9, said flange having a reduced extension 10 carried thereby. The upper end of said arm is provided with a head 11, said head having oppositely inclined surfaces 12 which serve to permit the trip arm 13 carried by the locomotive or a car to ride freely thereover after contact therewith. This arm 13 is connected in any suitable manner with the air brake system of the train so that when it is actuated the air pressure will be reduced and the brakes automatically applied.

A coil spring 14 is employed and has one terminal fixed to the lug 15 carried by the platform 3, the other terminal of said spring being fixed to the plate 6, the coil of the spring being engaged around a stud 16 mounted on said platform. This spring normally tends to move the plate 6 outwardly, and when it is desired to set the device a pin 17 is inserted in the perforation 7 which registers with a perforation 18 formed in the platform, said pin being engaged against the adjacent guide 5, and consequently holds the plate in its operative position, and at which time one portion of said plate overlaps the extension 10 of the flange 9, thereby holding the arm 8 in its vertical or operative position. The outer end of the platform 3 has formed integral therewith a support 19, said support having associated therewith a pair of horizontally disposed outwardly bowed arms 20 which are positioned in a plane below the outer end of the plate 6. The support is provided with an opening 21 and in which is engaged the pin 22 of the fusee 23, said fusee being held in an inclined position to prevent accidental disengagement by the arms 20.

To set the device it is only necessary to force the plate 6 inwardly so that the pin

17 can be placed in the registered perforations 7 and 18, and at which time the arm 8 will be held in its vertical or operative position so that a passing train will be automatically stopped when the trip arm 13 contacts with the head 11.

It is sometimes necessary that the fusee 23 be used to hold the plate 6 in its set position to hold the arm 8 in its operative position, and it will be apparent that as soon as the fusee burns down to a point in line with the outer end of the plate 6 that said plate will be released, and the spring 14 will force the same outwardly, thus freeing the extension 10 and permitting the arm 8 to swing downwardly and out of the way so that should another train equipped with a tripping arm travel over the track it will not be stopped. The arm 8 is inclined slightly outwardly so that when the fusee burns down and releases the plate 6 the weight of the arm will cause the same to swing out of the way.

What is claimed is:

1. A device of the class described comprising a clamp for detachable engagement with a rail, a platform supported by the clamp, an arm pivotally supported by the platform, a plate adapted to hold the arm in its operative position, and detachable means for positively holding the plate in a position to hold the arm in its operative position.

2. A device of the class described comprising a resilient clamp adapted for detachable engagement with a rail, a platform

supported by the clamp, an arm pivotally supported on the platform and having a flange carried thereby, a plate slidably mounted on the platform and adapted to cooperate with the flange to hold the arm in its operative position.

3. A device of the class described comprising a clamp for detachable engagement with a rail, a platform supported by the clamp, an arm pivotally supported by the platform, a spring pressed plate cooperatively associated with the arm to hold the same in a vertical or operative position, and means for supporting a fusee in a position to hold the plate in such position as to hold the arm in its operative position, said plate being released when the fusee burns to a predetermined point.

4. A device of the class described comprising a clamp adapted to detachably engage a rail, a platform carried by the clamp, a support carried by the platform for supporting a fusee, a plate slidably mounted on the platform and having one end adapted to engage the fusee, an arm pivotally supported by the platform and having an extension cooperative therewith for engagement with the plate to hold the arm in its operative position, and yieldable means for sliding the plate in one direction, when the fusee burns to a predetermined point, for releasing said arm, as and for the purpose set forth.

In testimony whereof I affix my signature. 70

ALBERT H. A. SCHUMACHER.
